UNITED STATES PATENT OFFICE.

LOUIS EMILE DUBOIS, OF TORONTO, CANADA.

LIFE-SAVING GUARD FOR CARS.

SPECIFICATION forming part of Letters Patent No. 527,270, dated October 9, 1894.

Application filed November 20, 1893. Serial No. 491,517. (No model.)

To all whom it may concern:

Be it known that I, LOUIS EMILE DUBOIS, merchant, of the city of Toronto, in the county of York and Province of Ontario, Canada, have invented certain new and useful Improvements in Life-Saving Guards for Cars; and I hereby declare that the following is a full, clear, and exact description of the same.

The object of this invention is to provide a trolley, cable or tram-car with a guard which, in the event of a person getting in front of or in the way of a moving car, will pick up and carry the person until the car can be brought to a standstill, or the person removed from danger.

It is also part of the object of my invention to so arrange the guard that it can be raised into and carried in a vertical position during the travel of the car when not required for service, and also to so arrange the guard that it can be instantaneously lowered to approximately the level of the rails the moment it is required to remove or pick up the person or object in danger of being run over by the moving car, and also to so arrange the guard that if desired it can be carried permanently in its lowered position; and it is also part of my invention to so arrange a switch in conjunction with the mechanism operating the trolley guard, that during the lowering movement of the trolley guard the operating mechanism will instantaneously cut off the circuit of the electric current from the motor, and during the raising of the trolley guard the operating mechanism for the same will move the switch to cut in the electric current to the motor, and also to so arrange the switch that it can be moved independently of the mechanism operating the trolley guard, in order that it can be operated at the will of the party running the car, the whole device being constructed and arranged as hereinafter more fully set forth and more particularly pointed out in the claims.

In the drawings: Figure 1 is a perspective view of a section of a car and guard showing the guard in its lowered position. Fig. 2 is a perspective view of the same showing the guard in its raised position. Fig. 3 is a perspective view of a section of the platform showing the switch mechanism, and Fig. 4 is a view of the under side of the same. Fig. 5

is a detail perspective view of a portion of the operating mechanism. Fig. 6 is a cross sectional view on the lines *a—a* Fig. 5. Fig. 7 is a view showing a spring employed in place of the counter balance.

Like numerals of reference refer to like parts throughout the specification and drawings.

Connected to each side of the platform 1 and beneath the same are two hangers respectively 2^a and 2^b provided with bearings 3^a and 3^b respectively for the spindle 4.

The spindle 4 is supported in the bearings 3^a and 3^b and extends from side to side of the platform 1 and about midway between the under side of the platform and the level of the roadway. Removably fitted to the one end of the spindle 4 is a bracket 5^a, and removably fitted to the opposite end of the said spindle is a bracket 5^b.

Formed within the bracket 5^a is a slot 6^a, and rigidly secured within the slot 6^a are the ends of two blocks 8^a arranged one on either side of the side bar 7^a. Passing through the blocks 8^a and the side bar 7^a is a bolt or pin by means of which the side bar is pivotally connected to the blocks 8^a. The bracket 5^b is provided with a similar slot 6^b to receive the ends of two blocks 8^b, arranged one on either side of the side bar 7^b, the side bar 7^b being connected to the said blocks in the same manner as the side bar 7^a is connected to the blocks 8^a.

Passing around the blocks 8^a and side bars 7^a is a clip 9^a binding two springs 10^a to the side bar 7^a and blocks 8^a while a similar clip 9^b binds two springs 10^b to the side bar 7^b and blocks 8^b.

The side bars 7^a and 7^b are continued around the front of the guard and are welded, or otherwise secured, together and form the front 11 of the guard. I may, however, if I so desire, make the side bars and front of one continuous piece of metal.

The front 11 of the framework of the guard is padded with a cushion of cork, rubber or other suitable material in order that the front of the frame, when coming in contact with the obstacle, will strike the obstacle and lift it on the net work of the guard without causing it serious injury.

Connected to each of the side bars 7^a and

7^b at or near their front ends is a spindle 12, and mounted on the spindle 12 at either end thereof is a small wheel 13.

Located between the spindle 12 and the rear end of the side bars 7^a and 7^b and connected thereto is a cross bar 14.

Inclosing the cross bar 14 and the spindle 12, and connected to the front 11 and side bars 7^a and 7^b is a covering 15 of canvas or other suitable material, which provides what might be termed a floor or platform to receive the object picked up by the guard.

Connected to the top of the outer side of the dash board are a series of horizontal arms 16 and supported in the arms 16 is a bar 17 parallel with the front 11 of the framework and extending entirely across the front of the dashboard.

Connected to one end of the bar 17 is one end of a chain 18, while the opposite end of the chain is connected to the side bars 7^a and connected to the other end of the bar 17 is one end of a chain 19, while the opposite end of the chain is connected to the side bars 7^b.

It might here be stated that the chains 18 and 19 are connected to the side bars respectively at or near their front ends, and the object of these chains is to support the framework of the guard when the guard is in its lowered position.

Connected to the front end of the framework of the guard or to the canvas covering 15 is the lower end of the front of a netting 20, while the upper end of the front of the netting 20 is connected to the bar 17. The lower ends of the sides 21 of the netting 20 are secured respectively to the side bars 7^a and 7^b.

Connected to the bar 17 at or near its middle is one end of a rubber or elastic cord 22, while the opposite end of the said cord 22 is secured to the bar 14 or canvas covering 15. Connected to the bar 17 at regular intervals between its ends are the upper ends of a series of stay cords 23, while the lower ends of the stay cords 23 are connected to the cross bar 14 or canvas covering 15.

Mounted upon the spindle 4 immediately between the bearings 3^a and 3^b of the hangers 2^a and 2^b respectively is a counter balance or balance weight 24 which is intended to balance the weight of the guard and automatically raise the guard into a vertical position when not required for use. Rigidly secured to the spindle 4 is a bell crank lever 25, and connected to the end of the bell crank lever 25 is the lower end of a foot lever 26. The foot lever 26 is pivoted in a bracket 27 connected to the under side of the platform 1, and the upper end of this foot lever 26 passes through a slot formed in the platform 1. The foot lever 26 is fitted on its upper end with a pedal 29.

The slot in the platform is fitted with a metallic plate 30 having a corresponding slot 28 in order that the lever will not wear away

the woodwork of the platform, and at one end of the slot 28 in the plate 30 is a recess 31 and at the opposite end of the slot 28 is a recess 32 and into each recess enters the foot lever 26 when at its respective end of the said slot. By means of these recesses 31 and 32 the lever 26 is rigidly held at the desired end of the slot, and the guard by this means is held either in its raised or lowered position as required, and the lever is held in either of the said slots by a spring 26^a. Explanatory of this it might be stated that by moving the foot lever 26 to the forward end of the slot as shown in Fig. 1 of the drawings, the guard is lowered into the position shown in the said Fig. 1 and is there held until the foot lever is removed from the recess 31, and the counter balance raises the guard into a vertical position. Whenever the lever is moved to the rear or opposite end of the slot and enters the recess 22 the guard is lifted into the vertical position shown in Fig. 2 of the drawings.

As before stated the counter balance 24 is intended to balance the framework of the guard, and immediately the foot lever has been released from the recess 31 the counter balance commences to lift the guard into a vertical position. The only force that is required in the operation of the apparatus is sufficient pressure for the forward movement of the foot lever, which is so slight that it amounts to nothing, the apparatus being so evenly balanced. Connected to the foot lever 26 is a spring 33 which operates the switch 34 cutting the current into or out of circuit with the motor, the switch mechanism, it might be stated, being located on the under side of the floor of the platform with a small knob extending through a slot in the floor of the platform and moved by the spring 33.

The object of the wheels 13 on the spindle 12 is to prevent the front of the guard striking the ground during the oscillation or swinging of the car while traveling over uneven ground, and the object of the springs 10^a and 10^b is to reduce the strain on the framework of the guard when the car comes in contact with an obstacle of any description whatsoever. The netting 20 extends entirely across the front of the car, and is sufficiently flexible and soft to receive a body without causing it serious injury.

In Fig. 7 I have shown a spring to serve the same purpose as the counter balance 24.

Having thus fully described my invention, what I claim as new, and desire to secure by Letters Patent, is—

1. In a life saving guard for cars the combination with the car of a spindle pivotally connected to the car, a balance connected to the spindle, a framework rigidly connected to the ends of the spindle, a netting secured to the framework and to the car, a lever to operate the spindle, and a switch mechanism adapted to cut on or off the current to the

motor of the car, operated by the respective movement of the lever, substantially as set forth.

2. In a life saving guard for cars the combination with the car of a spindle pivotally connected thereto, a framework connected to the ends of the said spindle and adapted to be raised and lowered thereby, a balance mounted on said spindle and adapted to counter balance the framework, a bell crank lever connected to the spindle, a foot lever connected to the bell crank lever and pivotally connected to the car, said foot lever adapted to operate the spindle and move the guard into a vertical or horizontal position, a latch plate connected to the car and adapted to hold the foot lever in its adjusted position, a netting secured to the framework, and to the car, said framework having a cushioned front, a spindle connected to the front of the framework, wheels mounted upon said spindle and adapted to travel on the rails, a canvas covering connected to the side bars at the front to form a platform, substantially as set forth.

3. In a life saving guard for cars the combination with the car of a spindle pivotally connected to the car, a frame work connected to each end of the said spindle and moving therewith, a canvas platform connected to the front end of the framework, a netting connected to the canvas platform, and to a cross bar connected to the dash board, and means for moving the guard into a vertical or horizontal position as required, substantially as set forth.

4. In a life saving guard for cars the combination with the car of a spindle pivotally connected to the car, a frame work connected to each end of the said spindle and moving therewith, a canvas platform connected to the front end of the framework, a netting connected to the canvas platform, and to a cross bar connected to the dashboard, and means for moving the guard into a vertical or horizontal position as required, and a switch mechanism adapted to cut on or off the current from the motor as required operated by the respective movement of the operating mechanism of the guard, substantially as set forth.

5. In a life saving guard the combination with the car of a spindle pivotally connected thereto, a bracket secured to each end of the spindle, a framework, the end of each of the side bars of the framework pivotally connected to its respective bracket, a spring connected to and adapted to bear down the said side bars, and means for moving the framework into a horizontal or vertical position, a netting secured to the framework and to the dashboard of the car, substantially as set forth.

6. In a life saving guard the combination with the car of a spindle pivotally connected thereto, a bracket secured to each end of the spindle, a framework, the end of each of the side bars of the framework pivotally con-

nected to its respective bracket, a spring connected to and adapted to bear down the said side bars, means connected to the spindle to counter balance the framework, a bell crank lever connected to the spindle, a foot lever pivotally connected to the car and to the bell crank lever, said foot lever and bell crank lever adapted to operate the said spindle substantially as set forth.

7. In a life saving guard the combination with the car of a spindle pivotally connected thereto, a bracket secured to each end of the spindle, a framework, the end of each of the side bars of the framework pivotally connected to its respective bracket, a spring connected to and adapted to bear down the said side bars, means connected to the spindle, to counter balance the framework, a bell crank lever connected to the spindle, a switch mechanism adapted to be operated by the movement of the foot lever to respectively cut on or off the current to the motor, substantially as set forth.

8. In a life saving guard for cars the combination of the car hangers connected to the under side of the platform of the car having bearings to receive a spindle, a spindle mounted in the bearings of the hangers, a bracket connected to each end of the spindle, a frame work composed of two side bars the ends of which are connected to the said brackets, and a cushioned front, a spindle connected to the front end of the side bars, wheels mounted on the spindle, a canvas covering connected to the side bars on the front forming a platform, arms connected to the outer side of the dashboard, a cross bar carried by said bars, a netting, the upper end of which is secured to the cross bar, and the lower end connected to the framework, a chain connected to each end of the cross bar and to the framework, an elastic cord connected to the middle of the cross bar and to the framework, a balance weight connected to the spindle and adapted to counter balance the guard, a bell crank lever connected to the spindle, a foot lever passing through the platform the lower end of which is connected to the bell crank lever, and the upper end fitted with a pedal substantially as described.

9. In a life saving guard for cars the combination with the car of hangers secured to the under side of the platform of the car, bearings forming part of the hangers, a spindle mounted in said bearings and extending across the car, a bracket mounted on each end of the spindle, a framework, the ends of the side bars of which are mounted in said brackets, springs connected to said side bars and bearing against said brackets, a cushioned front connected to the said bars, a spindle connected to the front of the said bars, wheels mounted on said spindle, a canvas covering connected to the side bars and to the front, a netting connected to the front of the framework, and to a cross bar held by

arms connected to the car, an elastic cord connected to the cross bar and to the front of the framework, stay or guy ropes connected to the cross bar and to the front of the framework, chains connected to the ends of the cross bar and to the framework, a balance weight connected to the spindle and adapted to lift the guard into a vertical position, a compound lever connected to the spindle a foot lever passing through a slot in the platform, the lower end of the foot lever connected to the compound lever, a plate inclosing the slot

having a corresponding slot therethrough, and recesses at each end of the slot, springs to throw the foot lever into either of the said recesses, a switch, a spring connected to the foot lever and adapted to move the switch, to either cut in or out the current to the motor, substantially as specified.

Toronto, November 4, 1893.

LOUIS EMILE DUBOIS.

In presence of—

F. J. DUNBAR,
P. H. DRAYTON.
